UNITED STATES PATENT OFFICE.

ALBERT SCHINKEZ, OF CHARLOTTE, MICHIGAN, ASSIGNOR TO HARRY W. HANCOCK,
OF CHARLOTTE, MICHIGAN.

PRESSURE-INDICATOR.

1,227,080.

Specification of Letters Patent. Patented May 22, 1917.

Application filed July 31, 1916. Serial No. 112,386.

To all whom it may concern:

Be it known that I, ALBERT SCHINKEZ, a citizen of the United States, residing at Charlotte, in the county of Eaton and State of Michigan, have invented certain new and useful Improvements in Pressure-Indicators, of which the following is a specification.

This invention relates to a device for indicating whether or not a fluid-conducting system, as, for example, a system for supplying oil to the bearings of an automobile power plant, is under pressure.

In the accompanying drawings, Figure 1 is a front elevation of an indicator embodying the features of my invention. Fig. 2 is a vertical central sectional view taken in the plane of dotted line 2 of Fig. 1. Fig. 3 is a section on dotted line 3—3 of Fig. 2. Fig. 4 is a view taken in the plane of dotted line 4—4 of Fig. 2. In Figs. 1 to 4 inclusive, the parts are in the same position. Fig. 5 is a view similar to that of Fig. 4, but showing the parts in position indicating that the system is under pressure.

The indicator may be located and supported in any suitable place or manner. Herein I have shown the indicator as located upon the dash A. The indicator comprises a circular case 1 having a rear wall 2 and a front wall 3. Adjacent to the rear wall 2 is a partition 4 spaced slightly away from said rear wall. Between the wall 2 and the partition 4 is a diaphragm 5, the periphery of which has a fluid-tight connection with the casing. The space between the rear wall 2 and the diaphragm 5 communicates with the oiling system or other fluid-conducting system in any suitable manner, as by means of a tube 6.

A rocking indicator member 7 formed from an integral piece of sheet metal and comprising the aligned pivots 8 and 9 is pivotally supported in any suitable manner within the space between the front wall 3 and the partition 4. Herein the ends of the pivots 8 and 9 are shown as pointed and as lying within sockets or bearings 10 in the peripheral portion of the case 1. The rocking member 7 comprises two arms 11 and 12 extending forwardly from the pivots 8 and 9, said arms supporting a plate 13 which may, as herein shown, be curved upon the arc of a circle concentric with the pivots 8 and 9. In the front wall 3 is a sight-open-

ing 14 through which a portion of the outer surface of the plate 13 is visible. On said plate may be placed any suitable indications, as, for example, the words "Off" and "On." When the rocking member 7 is in the position indicated in Fig. 4, the word "Off" is visible through the sight-opening 14. When the rocking member is in the position shown in Fig. 5, the word "On" may be read through said sight-opening.

The means for rocking the member 7 comprises an arm 15 extending from the pivot 8 in the direction opposite to the arms 11 and 12. One end of a spring arm 16 is suitably connected to the partition 4. The free end of the arm 16 normally bears against the arm 15 and thus holds the rocking member in the position shown in Figs. 1 to 4, inclusive. Means is provided for moving the arm 16 to the opposite side of the pivot 10 in order that said arm shall bear against the arm 11 as shown in Fig. 5 and thus cause the rocking member to assume the position shown in said figure. The means referred to includes the diaphragm 5 and a stud or projection 17 interposed between the diaphragm and the arm 16, said stud extending freely through an opening in the partition 4. Pivotal movement of the rocking member 7 is limited by engagement of the lugs 18 with the partition 4.

The sight opening 14 is covered by a glass disk 19 held in contact with the front wall 3 by means of a flanged ring 20 which is secured to the case 1 by any suitable means, as, for example, by soldering, said ring being adapted to be secured to the dash A or any other suitable support by means of screws 21 or the like.

When the system with which the tube 6 communicates is under pressure, the diaphragm 5 holds the arm 16 at the forward side of the pivot 8 and hence in contact with the arm 11 as shown in Fig. 5, whereby the member 7 is held in such position as to display the word "On" through the said opening 14. As soon as the pressure is removed or materially lowered, the arm 16 (by reason of its resiliency) passes to the other side of the pivot 8 and into engagement with the arm 15, thereby rocking the member 7 into the position shown in Fig. 4 whereby the word "Off" becomes visible through the opening 14.

I would have it understood that the in-

vention is not limited to the construction and arrangement of parts herein disclosed as various modifications may be made within the scope of the appended claims.

5. I claim as my invention:

1. A pressure indicator having, in combination, a case comprising a front wall, a rear wall and an intermediate partition, said partition having an opening therethrough, 10 an indicator member pivotally supported in the space between the front wall and the partition, said member having arms extending from opposite sides of the axis of said member, a spring arm secured to the partition, the free end of said arm being arranged 15 to bear against either of the first mentioned arms, a diaphragm in the space between the rear wall and the partition, and a stud between the diaphragm and the spring arm, 20 said stud extending through the opening in the partition, the front wall having an opening through which a portion of the indicator member is visible.

2. A pressure indicator having, in combination, a case, a sheet-metal indicator member within said case, said member comprising two aligned pivots, two arms extending in one direction from said pivots, an indication-bearing plate connected to said arms, and a third arm extending in the opposite direction from one of the first mentioned arms, a spring arm secured in the case, the free end of said arm being arranged to bear against either the third arm or one 35 of the first mentioned arms, and a diaphragm in said case arranged to move said spring arm from the third arm to one of said first mentioned arms.

3. A pressure indicator having, in combination, a case, a pivot, two arms extending

in opposite directions from said pivot, an arm secured in the case, the free end of said arm being arranged to bear against either of the first mentioned arms, a diaphragm in said case arranged to move said arm from 45 one to another of said first mentioned arms, and an indicating device operable by the first mentioned arms.

4. A pressure indicator having, in combination, a pivotally-supported indicator 50 member having arms extending from opposite sides of the axis of said member, a spring arm arranged to bear against either of said first mentioned arms, and a pressure-responsive member arranged to move said 55 spring arm from one of the first mentioned arms to the other.

5. A pressure indicator having, in combination, two oppositely-extending arms, a spring arm arranged to bear against either 60 of said first mentioned arms, a pressure-responsive member arranged to move said spring arm from one of the first mentioned arms to the other, and an indicating device 65 operable by said arms.

6. A pressure indicator having, in combination, a case having a sight opening therein, a curved plate bearing a plurality of indications, said sight opening being large 70 enough to permit one of said indications to be seen and too small to permit two indications to be seen at the same time, said plate being pivotally supported within the case behind the sight opening, a pressure-responsive device, and connections between said device and the plate for rocking the latter. 75

In testimony whereof, I have hereunto set my hand.

ALBERT SCHINKEZ.
